(57) **CLAIM**

The ornamental design for a pistol-to-carbine converter, as shown and described.

DESCRIPTION

FIG. 1 is a front perspective view of the claimed pistol-to-carbine converter showing my new design, in an unfolded orientation;

FIG. 2 is a bottom view thereof;

FIG. 3 is a top view thereof;

FIG. 4 is a front view thereof;

FIG. 5 is a rear view thereof;

FIG. 6 is a right side view thereof; and,

FIG. 7 is a left side view thereof holding a pistol, by way of example.

The broken lines are for illustration purposes only and form no part of the claimed design.
